US0D1046815S

(12) **United States Design Patent** (10) **Patent No.:** **US D1,046,815 S**
(45) **Date of Patent:** **** Oct. 15, 2024**

(54) **LOUDSPEAKER**

(71) Applicant: **Harman International Industries, Incorporated**, Northridge, CA (US)

(72) Inventor: **Rafal Mateusz Czaniecki**, Shenzhen (CN)

(73) Assignee: **Harman International Industries, Incorporated**, Northridge, CA (US)

(**) Term: **15 Years**

(21) Appl. No.: **29/866,206**

(22) Filed: **Sep. 1, 2022**

(51) **LOC (14) Cl.** **14-01**

(52) **U.S. Cl.**

USPC **D14/221**; D14/214

(58) **Field of Classification Search**

USPC D14/167, 168, 170–172, 188, 193–198, D14/203.1–203.8, 204, 209.1, 210–217, D14/219, 221, 222, 224, 239, 496

(57) **CLAIM**

The ornamental design for a loudspeaker as shown and described.

DESCRIPTION

FIG. 1 is a top perspective view of a loudspeaker showing the new design;

FIG. 2 is a front elevational view thereof;

FIG. 3 is a rear elevational view thereof;

FIG. 4 is a side elevational view thereof;

FIG. 5 is an opposite side elevational view thereof;

FIG. 6 is a top view thereof; and,

FIG. 7 is a bottom view thereof.

The broken lines illustrate portions of the loudspeaker that form no part of the claimed design.

1 Claim, 7 Drawing Sheets
